GEORGE S. WEINERTH, OF READING, PENNSYLVANIA

CONTROLLING MECHANISM FOR FULL FASHION TEXTILE MACHINES

Application filed March 27, 1930. Serial No. 439,289.

This invention relates to control mechanism for full fashion textile machines whereby the length of hosiery can be accurately regulated and has for its primary object the design and correlation of mechanisms whereby the control rod of the textile machine may be automatically manipulated directly from a movable part of the machine according to the number of the rotations of the take-up 10 shaft.

Another object of the invention resides in the provision of mechanism whereby the number of turns made by a take-up shaft in the winding of the hosiery will automatically 15 control the operation of the control rod of the textile machine from a power shaft thereof.

Another object of this invention relates to the arrangement of manually adjustable 20 mechanism with manipulating mechanism and release mechanism whereby the periodic operation of the release mechanism which controls the operation of the manipulating mechanism can be manually regulated.

Another object of this invention resides in the design of and the operation of automatic mechanism directly off the take-up shaft for periodic manipulation of the control rod of the machine whereby the machine is periodically 25 stopped and started.

A feature of the invention resides in the direct relation of the control rod with the control mechanism whereby the latter may be automatically reset in the manipulation of the control rod manually.

Another feature of the invention resides in the novel construction, design and association of the various parts of the various mechanisms whereby the mechanisms may be 30 periodically thrown into operative connection with the movable part of the machine for the manipulation of the control rod according to the length of the hosiery desired.

My invention is also distinguished in a 35 design of mechanism that is directly controlled by the length of the hosiery as the same is manufactured thereby assuring accurate length of all portions of the hosiery.

With these and other objects in view the 40 invention will be better understood from the

following detailed description taken in connection with the accompanying drawings wherein—

Figure 1 is a front elevation of the invention.

Figure 2 is a side elevation.

Figure 3 is a detailed elevation of a portion of the mechanism.

Figure 4 is a sectional view adjacent to the slide.

Figure 5 is a cross sectional view thru the rack bar and one of the tappets.

Figure 6 is a detailed view of the catch and associated parts.

Figure 7 is a blank view of a full fashion 65 stocking.

Again referring to the drawings illustrating one of the many constructions of my invention, 1 designates one of the power shafts or cam shafts of a full fashion textile machine to which is directly connected a cam 2.

The take-up shaft 3 of the textile machine is arranged contiguous to the control rod 4 so that my improved mechanism may have a 70 direct operative relation with the shaft 3 and the control rod 4.

My invention consists basically of manipulating mechanism, release mechanism, tripping mechanism and setting mechanism, all 75 of which are so correlated that the manipulating mechanism is periodically moved into operative engagement with cam 2 by the release mechanism, the latter in turn depending for its operation upon release of the trip mechanism that is under direct control of 80 the take-up shaft 3.

The setting mechanism is so designed that in the manual manipulation of the control rod 4, the releasing mechanism will be automatically reset.

Manipulating mechanism

The manipulating mechanism consists of a member or slide 9 mounted in guide bearings 10 and carrying a roller 11 directly related with the cam 2. As this slide 9 has a pivotal connection 12 with the connecting rod 13 it will be appreciated that the slide 9 may be swung laterally to move the same 85 into and out of the path of travel of the 90 connecting rod 13.

cam 2. The connecting rod 13 has a pivotal connection 14 with one arm of a bell crank 15 that is connected to the control rod 4 so that upon movements of the rod 13 the 5 control rod 4 will be manipulated through the bell crank 15.

Release mechanism

10 The release mechanism consists of a bell crank lever 16 having a direct connection with the slide block 17 that is provided with the groove 18, the walls of which form bearings for one limb of the arm 9. The bell crank lever 16 has a pivotal connection 19 with a link 20 which in turn is connected to a second bell crank lever 21 carried by a bracket 22. This bell crank lever 21 is constantly urged in a downwardly direction by a spring 21b attached thereto and having its 15 other end secured to the bracket 22. This spring is utilized to urge link 20 downwardly when released as hereafter set forth.

Tripping mechanism

25 The tripping mechanism consists of a catch 23 fixed to the bell crank lever 21 by a pin member 23b so as to turn with the bell crank lever. This catch is of a crescent shape formation to cooperate with the pin member 23b to define a recess 23c for accommodating passage of associated parts under conditions herein set forth and further to provide proper locking engagement with trigger 24. The trip device consisting of the catch 23 and trigger 24 is arranged to be released by a plurality of tappets 25 adjustable on a rack bar 26 slidably mounted in a guideway 26b formed in the bracket 22 and this rack bar 30 is geared to the take up shaft 3 by the gear wheel 27. This rack bar 26 is provided with a track receiving the heads 28 of the tappets. The heads 28 are connected to dogs 29 designed and associated with the heads to swing in one direction only so that in the upward 35 movement of the tappets the trigger 24 will be disengaged from the catch 23 whereas in the return movement of the tappets the dog 29 will slide over the trip device thereby preventing manipulation thereof. The rack bar is manually returned to its normal 40 position by the turning of shaft 3 in the unwinding of the stocking leg blanks therefrom.

45 Each head 28 of the tappets 25 is provided with a set screw 30 by means of which the tappet may be fixed in any desired adjusted position along the rack bar 26. The main purpose of mounting such tappet in adjustable relation to the rack bar is to selectively control the stopping of the machine for varying the shape or construction of the finished stocking. To complete the invention, a link 31 is pivotally connected to the bell crank 15 and provided with a slot 32b 50 associated with a pin 32 carried by the bell

crank 21 for providing a loose connection between the bell crank 21 and link 31.

In the diagrammatic view, Figure 7, I have designated by the numerals 1 to 6, the various stages in the construction of the hosiery blank 70 where the machine will be automatically stopped by my control mechanism. It is, of course, to be understood that the distance between each stop and the number of stops may be varied at will by changing the number of and relation of the tappets.

75 The relative arrangement of the pin 32 and walls of the slot 32b is a very important feature of my invention as this accommodates proper resetting of the mechanism when the control rod 40 is manually manipulated. In other words, the pin 32 is positioned in the slot 32b and the length of the slot is of a degree that when the machine has been stopped automatically by the turning of the control rod 4 by the connecting rod 13, the link 31 will slide free of the crank lever 21 but upon manual turning of the control rod 4 in the reverse direction to start the machine the engagement of the pin with an end portion of the slot will cause movement of the bell crank 21 and the resetting of the device to be automatically operated at another predetermined point in the operation of a textile machine.

80 In the operation of the invention the various tappets are set accurately along the rack bar so as to periodically and successively engage and trip the trigger 24 for allowing the bell crank 21 to turn about its pivot and slide the link 20. Movement of the link 20 90 manipulates the slide block 17 which in turn moves the roller 11 into operative relation with the cam 2. In the rotation of the power shaft 1, the cam 2 will move the slide 9 vertically, the slide in turn moving the connecting rod 13 for giving a partial turn to the bell crank 15. As the bell crank 15 is fixed to the control rod 4, it will be understood that the control rod is turned the required degree to 95 stop the textile machine. Due to the pin and slot connection 32 between the link 31 and the bell crank 21, full movement of the control rod 4 to a position to start the machine will move the bell crank 15 the required degree to reset the trigger 24 into engagement with the catch 23 for repeating the operation 100 of the mechanism. In other words, the relation of the pin 32 and walls of the slot 32b are such that the cam 2 is capable of moving upwardly the connecting rod 13 and through it the bell crank 15 to turn the control rod 4 and automatically stop the machine. When 105 this is taking place the link 31 rides freely of the bell crank 21 thereby not interfering in any way whatsoever with the operative relation of the roller 17 with the cam 2. This movement of the link 31 to a predetermined extent brings into proper cooperative relation one end wall of the slot 32b and the pin 110 32 so that when the rod 4 is manually moved 115

in the opposite direction to start the textile machine engagement between an end wall of the slot 32b and the pin 32 will cause the bell crank 21 to turn in the proper direction 5 to elevate link 20 and through the bell crank 16 bring the roller 17 out of operative relation with the cam 2 so that the entire mechanism will be reset for another cycle of operation at the proper time, that is to say, when 10 a dog 25 comes into proper engagement with the trigger 24.

Attention is called to the fact that my mechanism automatically moves the control rod in a direction to stop the machine and the 15 control rod in its movement automatically resets my control mechanism for passage through another cycle of operation when released by another tappet. As the gear 27 is fixed to the take up shaft of the textile machine and the take up shaft is directly connected to the stocking being formed and further the gear has a fixed connection with the rack bar, it will be understood that movement of the rack bar is in accurate relation to the 20 length of the stocking being formed and therefore accurate engagement of each tappet with the trip device in accordance with the length of the hosiery as being manufactured. In the removing of the stocking as mounted 25 around the take up shaft 3, the rack bar is automatically moved towards its normal position, the dogs 25 passing freely by the trip device due to their pivotal connection with the heads of the tappets.

30 In concluding, I wish to stress the fact that I am of the opinion that I am the first to interpose automatic control mechanism between the power shaft and the control shaft of a full fashion textile machine, and further interpose control mechanism between the power shaft, control rod and the hosiery take up shaft, whereby in the wrapping of the hosiery as manufactured, the take up shaft will automatically control 40 the operation of the manipulating mechanism from the power shaft for automatically operating the control rod to stop the textile machine.

I am of the opinion, that I am the first to 45 arrange automatic control mechanism to take its power directly off the textile machine in accordance to the extent of travel of the take up shaft of the textile machine. Therefore, I am entitled to broad protection for the new 50 combination set forth irrespective of the construction of component parts which may be modified many ways without departing from the spirit of my invention and therefore I do not desire to be limited in protection in 55 any manner whatsoever except as set forth 60 in the following claims.

What I claim is:

1. A controller for full fashion textile machines comprising in combination with the 65 control rod, take-up roll and main cam shaft

of a textile machine, mechanism periodically operated by the cam shaft and under the control of said take-up roll for automatically operating said control rod shaft.

2. A controller for full fashion textile machines comprising in combination with the main cam shaft, take-up roll and control rod thereof, automatic mechanism under the control of said take-up roll for periodic operation by said cam shaft, said mechanism automatically operating said control rod, according to the travel of said take-up roll.

3. A controller for full fashion textile machines comprising in combination with the take-up shaft and cam shaft of a textile machine, mechanism operatively related with said take-up shaft and cam shaft whereby the said mechanism will be periodically operated for controlling the operation of the textile machine according to movements of 85 said take-up shaft.

4. In combination with the cam shaft, control rod and take-up shaft of a full fashion textile machine, control mechanism connected with said control rod to manipulate the same and adapted to be set into operative engagement with said cam shaft by said take-up shaft when said take-up shaft has been rotated a predetermined number of 90 turns.

5. In combination with the cam shaft, control rod and take-up shaft of a full fashion textile machine, control mechanism comprising manipulating mechanism directly connected to said control rod and release mechanism for releasing said manipulating mechanism for movements into operative and inoperative connection with said cam shaft in accordance with the number of rotations of 100 said take-up shaft.

6. In combination with the cam shaft, control rod and take-up shaft of a full fashion textile machine, control mechanism comprising manipulating mechanism directly connected to said control rod and operatively associated with said cam shaft and release mechanism under the control of said take-up shaft and operatively related with said manipulating mechanism to move the same into and out of operative engagement with the said cam shaft according to the number of rotations of the said take-up shaft.

7. In combination with the main power shaft, control rod and take-up shaft of a full fashion textile machine, control mechanism comprising manipulating mechanism operatively connected with the said control rod, release mechanism under the control of said take-up shaft adapted upon being released to gravitate to a position to move said manipulating mechanism into operative engagement with said power shaft.

8. In combination with the power shaft, control and take-up shaft of a full fashion textile machine, control mechanism comprising 130

- ing a cam mounted on said power shaft, manipulating mechanism associated with said cam and operatively connected with said control rod and release mechanism periodically released by said take-up shaft in accordance with the movements thereof for moving said manipulating mechanism into operative engagement with said cam.
9. In combination with the said cam shaft, 10 take-up shaft and control rod of a full fashion textile machine, control mechanism comprising manipulating mechanism operatively connected to said control rod and including a member adapted to be moved into operative engagement with said main cam shaft, said release mechanism for moving said member into operative engagement with said main cam shaft, and tripping mechanism under the control of said take-up 20 shaft for operating said releasing mechanism.
10. In combination with the main cam shaft, take-up shaft and control rod of a full fashion textile machine, control mechanism comprising manipulating mechanism directly connected to the control rod and including an adjustable member for movement into and out of operative engagement with said cam shaft, release mechanism for manipulating said member and manually adjustable tripping mechanism operatively associated with said release mechanism and said take-up shaft to time the operation of said release mechanism according to the rotation of said take-up shaft.
11. In combination with the main cam shaft, take-up shaft and control rod of a full fashion textile machine, manipulating mechanism operatively connected to said control rod and mounted for movements into and out of operative engagement with said main cam shaft, release mechanism for moving said manipulating mechanism into and out of operative engagement with the main cam shaft, manually adjustable tripping mechanism adapted to periodically release said released mechanism according to the rotatable movements of said take-up shaft and mechanism operatively connected with said control rod and with said releasing mechanism to reset the latter according to manipulations of said control rod.
12. In combination with a power shaft, take-up shaft and control rod of a full fashion textile machine, a cam mounted on said power shaft, a slide mounted for displaceable movements into and out of operative engagement with said cam, a connecting rod connecting said slide with said control rod for the manipulation of the latter, release mechanism for moving said slide into and out of operative engagement with said cam, a trip device for release of said release mechanism, a rack bar operatively connected with 55 said take-up shaft and tappets adjustably mounted on said rack bar for periodic engagement with said trip device for release of the same to allow said release mechanism to manipulate said slide.
13. In combination with a power shaft, 70 take-up shaft and control rod of a full fashion textile machine, a cam mounted on said power shaft, a slide mounted for displaceable movements into and out of operative engagement with said cam, a connecting rod connecting said slide with said control rod for the manipulation of the latter, release mechanism for moving said slide into and out of operative engagement with said cam, a trip device for release of said mechanism, a rack 75 bar operatively connected with said take-up shaft and tappets adjustably mounted on said rack bar for periodic engagement with said trip device for release of the same to allow said release mechanism to manipulate said slide, and setting mechanism having an operative connection with said control rod and said trip device for the resetting of the latter.
14. In combination the power shaft, take-up shaft and the control rod of a full fashion textile machine, a cam mounted on said power shaft, a slide operatively related with said cam, a connecting rod connecting said slide with said control rod, an actuator for swinging said slide into and out of operative engagement with said cam, a catch connected to said actuator, a trigger for holding said catch in a predetermined position, a rack bar having an operative connection with said take-up shaft, tappets adjustably mounted on said rack bar for periodic contact with said trigger to release the same from said catch to allow said actuator to manipulate said slide.
15. In combination the power shaft, take-up shaft and the control rod of a full fashion textile machine, a cam mounted on said power shaft, a slide operatively related with said cam, a connecting rod connecting said slide with said control rod, an actuator for swinging said slide into and out of operative engagement with said cam, a catch connected to said actuator, a trigger for holding such catch in a predetermined position, a rack bar having an operative connection with said take-up shaft, tappets adjustably mounted on said rack bar for periodic contact with said trigger to release the same from said catch to allow said actuator to manipulate said slide, a link operatively connected to said control rod and having a pin and slot connection with said catch to reset the same according to the manipulation of said control rod.
- In witness whereof I have hereunto set my hand.
- GEORGE S. WEINERTH.
